CHAIR CONSTRUCTION

Andrew Roth, Philadelphia, Pa., assignor to
 Bunting Glider Company, Philadelphia, Pa., a
 corporation of Pennsylvania

Application May 17, 1945, Serial No. 594,300

4 Claims. (Cl. 155—194)

1

This invention relates generally to chairs and the like and more particularly to an improved construction of an all-metal chair.

Among the principal objects of the present invention is to provide an all-metal chair which is exceedingly rigid in construction by reason of the employment of side frame elements for the seat and back panels, these frame elements serving not only as rigidifying members for these panels but also as the means for supporting the seat and back elements upon the supporting frame for the chair. Further, these side frame elements are capable of being embossed or otherwise ornamented to enhance the appearance of the chair and so give it an appearance which is quite distinctive from the conventional construction of all-metal chairs.

Other objects and advantages of the invention will appear more fully hereinafter, it being understood that the present invention consists substantially in the combination, construction, location and relative arrangement of parts, all as described in detail hereinafter, as shown in the accompanying drawings and as finally pointed out in the appended claims.

In the accompanying drawings, which illustrate one embodiment of a chair constructed in accordance with the principles of the present invention,

Figure 1 is a perspective view of such chair;

Figure 2 is a side elevational view thereof;

Figure 3 is a vertical sectional view taken on the line 3—3 of Figure 1;

Figure 4 is a transverse sectional view through the seat portion of the chair taken on the line 4—4 of Figure 3;

Figure 5 is a perspective view showing in separated relation the frame elements for the seat and back panels as employed on one side of the chair;

Figure 6 is a vertical sectional view of one of the side frame elements for the seat panel as taken on the line 6—6 of Figure 5; and

Figure 7 is a sectional view taken on the line 7—7 of Figure 3.

Referring now more particularly to the drawings, it will be observed that the chair of the present invention includes a supporting frame 10 for a seat assembly 11 and a back assembly 12, the frame 10 consisting of a pair of laterally spaced identical side members 13—13, each of generally inverted U-shape, the portions 14 of which constitute the legs of the chair while the curved upper portions thereof serve as the chair arms.

2

The seat assembly 11 of the chair includes a seat panel 15 suitably formed of a sheet metal stamping which may be embossed, perforated or otherwise ornamented as desired, and a pair of laterally spaced frame elements 16—16 which respectively underlie and are secured to the opposite marginal side portions of the seat panel. As most clearly appears in Figures 4, 5 and 6, each of these side frame elements 16—16 for the seat panel 15 is of generally box-like form open on that side thereof which presents inwardly of the chair, the closed or main body portion 17 thereof being so disposed that it lies in the vertical plane of the side edge of the seat panel in flush relation therewith. The body portion 17 of each frame element is provided with a marginal inwardly extending flange 18, the seat panel being secured, as by welding, riveting or otherwise, the top and front flanged portions of the side frame, these portions being contoured to correspond to the desired shape of the seat panel. Thus, the seat assembly 11 is in the form of a rigid unit consisting of the relatively thin seat panel 15 and its reinforcing and rigidifying side frame elements 16—16. The front end of the seat panel extends downwardly about the front flanged portions of the side frame elements, as at 19, and thence rearwardly, as at 20, to provide a smooth depending frontal skirt for the seat. In similar manner, the rear end of the seat panel extends downwardly about the rear flanged portions of the side frame elements, as at 21, to provide the seat assembly with a smooth, finished rear edge. The front and rear edges of the seat panel are each cut away at their opposite ends to facilitate turning said edges substantially at right angles to the adjacent flanged portions of the frame elements, as at 22 in the case of the front edge of the seat panel and as at 23 in the case of the rear edge thereof. Preferably, the inturned front and rear edges of the seat panel are doubled back upon themselves as shown.

The back assembly 12 is structurally similar to that of the seat assembly in that it also includes a sheet metal panel 24 to the opposite side edges of which are respectively secured a pair of reinforcing and rigidifying frame elements 25—25. Except for differences in shape, these elements are structurally and functionally the same as those of the seat assembly 12. The top and bottom edges of the back panel 24 are wrapped about the top and bottom flanged portions of the frame elements 25—25 and then inwardly turned, as at 26 and 27, the inturned

portions being doubled upon themselves as shown to provide smooth, finished edges.

To assemble the seat and back assemblies, the flat rear end of the seat assembly is brought into abutting relation to the flat lower end of the back assembly and these abutting ends are then secured together by bolts 28 which extend through registering bolt holes 29 suitably provided in said abutting ends of the seat and back assemblies.

The assembled seat and back unit is in turn supported between the side members 13-13 of the chair by means of bolts or studs 30 which project through the front legs of the said members 13-13 and engage the vertically disposed main body portions of the frame elements 16-16, and bolts or studs 31 which similarly project through the rear arm portions of the members 13-13 and engage the vertically disposed main body portions of the frame elements 25-25. The seat and back unit thus suspended between the supporting members 13-13 interconnect the latter and cooperate therewith to form an exceedingly rigid and durable structure. Preferably, the rear legs of the side supports 13-13 are interconnected by a transversely extending connector rod or tube 32.

The box-like frame elements 16-16 and 25-25, which serve as side girders for the seat and back panels, so strengthen and reinforce the latter as to permit the use of light gauge sheet metal to form such panels. Also, an important advantage in the use of these frame elements is that their main body portions, which lie in flush relation to the side edges of the seat and back panels, may be embossed, perforated or otherwise treated to provide any desired decorative effect to the sides of the chair and so materially enhance its ornamental aspect. In the construction as illustrated, such ornamentation is obtained by a combination of embossing and perforating those side portions of the frame elements to provide perforations 33 and surrounding indented portions 34.

It will be understood, of course, that the present construction of chair is not in any sense limited to the particular form thereof shown in the drawing and that the seat and back assemblies may be varied as desired, particularly from the standpoint of design, all without departing from the principles of the present invention.

What is claimed as new and useful is:

1. In a chair of the character described, a pair of laterally spaced side members constituting supports for the seat and back of the chair, a seat assembly including a pair of laterally spaced side frame elements and a sheet metal panel extending therebetween and secured thereto, and a back assembly also including a pair of laterally spaced side frame elements and a sheet metal panel extending therebetween and secured thereto, said frame elements being characterized in that each includes a main body portion disposed substantially in the vertical plane of said edge of the panel and an inwardly turned flange extending marginally about said main body portion, the frame elements respectively secured to the cor-

responding sides of said seat and back panels being disposed with their flanged end portions in abutting relation, said flanged end portions being flattened for securement together in flatwise engagement.

2. In a chair of the character defined in claim 1 wherein the side frame elements for the seat assembly are respectively aligned with and secured to the corresponding elements for the back assembly to provide a unitary seat and back structure adapted for support between said side supporting members.

3. An all-metal seat and back assembly for a chair or the like adapted to be supported between a pair of side supports arranged in laterally spaced substantially parallel relation comprising a pair of angularly related sheet metal panels respectively constituting the seat and back of the chair, the corresponding side edges of said panels being disposed in a common vertical plane, and a structural element extending along substantially the full length of and being secured to each marginal side edge portions of said panels, said elements being characterized in that each includes a main body portion disposed substantially in said vertical plane of the side edge of the panel to which it is secured and an inwardly turned flange extending marginally about said main body portion, the flanged portions at the proximate extremities of the elements extending along each side of the angularly related seat and back panels being secured together in abutting relation.

4. An all-metal assembly for a chair or the like comprising a pair of laterally spaced elongated structural frame elements including main body portions disposed in substantially parallel relation, each of said body portions having an inwardly turned flange extending marginally about the full perimeter thereof to provide each frame element with flanged longitudinally extending edges and flanged extremities, a sheet metal panel supported by and secured to corresponding longitudinally extending portions of the peripheral flanges of said main body portions, with the opposite side edges of said panel substantially flush with the external surfaces of said main body portions, the opposite transverse ends of said panel being respectively extended about the corresponding flanged extremities of said frame elements.
